UNITED STATES PATENT OFFICE.

EUGENE J. RAY, OF BEVERLY, MASSACHUSETTS, ASSIGNOR TO UNITED SHOE MACHINERY COMPANY, OF PATERSON, NEW JERSEY, A CORPORATION OF NEW JERSEY.

DRIVING AND STOPPING MECHANISM.

1,193,061.

Specification of Letters Patent.

Patented Aug. 1, 1916.

Application filed September 19, 1914. Serial No. 862,490.

To all whom it may concern:

Be it known that I, EUGENE J. RAY, a citizen of the United States, residing at Beverly, in the county of Essex and State of Massachusetts, have invented certain new and useful Improvements in Driving and Stopping Mechanism; and I do hereby declare the following to be a full, clear, and exact description of the invention, such as 10 will enable others skilled in the art to which it appertains to make and use the same.

The present invention relates to driving and stopping mechanism particularly applicable to buttonhole sewing machines, but 15 also capable of use in other relations.

In the drawings hereinafter specifically described a preferred form of the invention is embodied in the buttonhole machine fully illustrated and described in the patent to 20 Hill, No. 1,063,880, June 3, 1913. In that machine two driving mechanisms are provided, one acting while the sewing mechanism is at rest to rotate the cam carrying actuating and controlling gear and the other 25 acting during the sewing of the buttonhole to rotate the cam carrying gear and also to actuate the sewing devices and rotate the supports in which they are mounted. The two driving mechanisms of the Hill ma- 30 chine are thrown into and out of operation by mechanism controlled by the controlling gear, the arrangement being such that one driving mechanism is thrown into operation as the other driving mechanism is thrown 35 out of operation. In the Hill machine, however, when the mechanism for actuating the sewing mechanism and rotating the supports in which this mechanism is mounted is thrown out of operation it is entirely dis- 40 connected from the cam carrying gear so that the gear in its continued rotation has no control over the mechanism for actuating and rotating the sewing mechanism and it is possible for this mechanism to be dis- 45 placed either accidentally or intentionally with relation to the cam carrying gear so that when the mechanism is again started the various parts of the machine do not have the proper timed relation. Also in the 50 machine of the Hill patent the construction and arrangement of the devices for starting the cam carrying gear into operation and for finally stopping it are such that the driving mechanism for the cam gear can not be 55 thrown into operation unless the gear is ro-

tated into such a position as to release the clutch actuating devices, and also in case the starting lever is kept depressed by the operator the machine will not stop at the completion of a cycle of operations, but will continue to operate so long as the lever is held depressed. 60

In applying the various features of the present invention to the machine of the Hill patent a driving mechanism has been embodied in the machine which comprises connections between the cam carrying gear and the mechanism for actuating and rotating the sewing devices which lock the mechanism for actuating and rotating the sewing 70 devices against displacement with relation to the cam carrying gear so that this mechanism can not be turned either intentionally or accidentally so as to get it out of the proper timed relation to the mechanism for 75 actuating the other parts of the machine. Also clutch actuating and controlling devices have been embodied in the machine by which the machine can be started regardless of the exact position of the cam carrying 80 gear and by which the machine will be prevented from making more than one complete cycle of operations, whether or not the starting lever is kept depressed. It will be understood, however, that while the specific 85 embodiment of the invention is particularly applicable to button-hole sewing machines of the type disclosed in the Hill patent, the several features of the invention are not limited to use in any particular type of ma- 90 chine, nor except as defined in the claims are they limited to any specific construction and arrangement of parts. 95

Referring now to the drawings; Figure 1 is a view in sectional elevation of so much 100 of the buttonhole sewing machine of Hill Patent No. 1,063,880 as is necessary to show the connection of the present invention therewith; Fig. 2 is a detail sectional plan view of the cam carrying gear and its driving mechanism; Fig. 3 is a detail view in side elevation of the clutch controlling devices of the mechanism for driving the cam carrying gear independently; and Figs. 4, 5 and 6 are views similar to Fig. 3 showing 105 the parts in different positions.

The upper needle of the machine is indicated at 1 and the lower needle at 2. The upper needle is eccentrically mounted in a bar 3 which reciprocates through a rotary 110

head mounted in the overhanging frame 4 of the machine. The lower needle, together with the devices which coöperate therewith in handling the lower thread is mounted in a 5 rotary turret 5 supported in the base of the machine. The sewing devices, including the upper and lower needles 1 and 2, are actuated through suitable connections from the driving shaft 6 and the sewing devices 10 are rotated through suitable connections from the rotary gear 7, all as fully illustrated and described in the patent to Hill above referred to. The button hole cutting lever of the machine is indicated at 8 and 15 is actuated as in the machine of the Hill patent through a pivoted lever from a cam on the cam carrying gear 9. The work clamps 10 of the machine are mounted upon a clamp carriage 11 and these clamps 20 and carriage are actuated and moved as in the machine of the Hill patent, the clamp being closed at the beginning of the cycle of operations of the machine by the movement of the cutter lever, and the clamp carriage 25 being moved longitudinally at the beginning and end of the sewing operation and also during the sewing operation by suitable connections from the cam carrying gear 9. The gear 7 from which the sewing devices 30 are rotated is driven as in the machine of the Hill patent through a pinion 12 at the lower end of a vertical shaft 13 which is connected at its upper end through a universal joint to a vertical shaft 14 carrying 35 at its upper end a worm gear 15 meshing with a worm on the driving shaft 6. For driving the cam carrying gear 9 independently of the gear 7 and the mechanism for actuating the stitch forming devices a second continuously rotating driving shaft 16 is provided as in the machine of the Hill patent, which shaft is provided with a worm meshing with a worm gear 17 mounted 40 loosely on the shaft 13. To secure the improved results hereinbefore referred to, however, novel mechanism has been provided for driving the cam carrying gear 9 from the worm 17 and for driving the cam carrying gear from the mechanism through 45 which the gear 7 is rotated.

When the machine is first thrown into operation the cam carrying gear 9 rotates while the gear 7 and the mechanism for actuating the sewing devices remain at rest. 50 After the gear 9 has made a part of a revolution the mechanism for independently driving the gear is thrown out of operation and the movement of the gear is continued through connections to the mechanism for 55 rotating the gear 7 and actuating the stitch forming devices, the mechanism for rotating the gear 7 and actuating the stitch forming devices being thrown into operation simultaneously with the throwing out of the 60 mechanism for independently driving the 65

cam carrying gear. The connections for driving the cam carrying gear 9 from the mechanism for actuating and rotating the stitch forming devices comprises a pinion 18 fast on the shaft 13 and arranged to mesh 70 with the cam carrying gear 9. To enable the mechanism for actuating and rotating the stitch forming devices to remain stationary during a portion of the revolution of the cam carrying gear the periphery of 75 the gear is provided with a blank space 19 arranged to register with the pinion 18 while the cam carrying gear is being driven independently, and in order to lock the mechanism for actuating and rotating the 80 stitch forming devices against displacement while the cam carrying gear is being driven independently the pinion 18 is provided at its lower end with a locking segment 20 and the cam carrying gear 9 is provided with a 85 coöperating locking plate 21. The locking plate 21 is in engagement with the locking segment 20 while the cam carrying gear is being driven independently and is out of engagement therewith while the cam carrying gear is being driven by the pinion 18. The mechanism for actuating and rotating the stitch forming devices is thus connected at all times to the cam carrying gear 9 and by no possibility can the timed relation of 90 this mechanism with relation to the cam carrying gear be altered, either intentionally or accidentally.

The connections between the worm gear 17 and the cam carrying gear 9 for driving 100 the cam carrying gear independently comprise a clutch member 22 mounted to rotate and slide longitudinally on the shaft 13, a clutch member 23 formed on the worm gear 17 arranged to coöperate with the clutch 105 member 22, and a pinion 24 fast on the clutch member 22 and meshing with the cam carrying gear 9. Upward movement of the clutch member 22 brings it into engagement with the clutch member 23 without raising pinion 24 high enough to disengage the 110 teeth of cam carrying gear 9, and thus connects the cam carrying gear to the shaft 16 so that it is driven from this shaft. Downward movement of the clutch member 22 disconnects the cam carrying gear from the 115 driving shaft 16 and leaves the clutch member 22 and pinion 24 free to be rotated idly by the cam carrying gear 9 while it is being driven by the pinion 18.

As is fully described in the patent to Hill above referred to, the driving shaft 6 is driven through a clutch which is opened and closed by mechanism including a clutch shifting rod which is controlled by a cam 125 on the cam carrying gear 9. This cam is indicated at 25 on Fig. 2 of the drawings. Also as is fully described in the Hill patent the shaft 6 is brought to rest when its driving clutch is opened by means of a brake 130

plunger, which plunger is also controlled by a cam on the cam carrying gear 9. In Fig. 2 of the drawings this brake plunger is indicated at 26 as mounted upon the end of an arm 27, the hub of which is provided with teeth meshing with teeth on a lever 27, the inner end of which extends into position to be acted upon by the cam 28 on the cam carrying gear 9.

10 The cam carrying gear 9 is also provided with two cams indicated at 29 and 30 on Fig. 2. These cams are arranged to act upon a clutch shifting lever which moves the clutch member 22 of the mechanism for independently driving the cam carrying gear into and out of engagement with the clutch member 23. The cam 29 acts upon the clutch shifting lever to stop the machine at the completion of the cycle of operations while the cam 30 actuates the clutch shifting lever to move the clutch member 22 out of engagement with the clutch member 23 just as the clutch for driving the shaft 6 is closed and holds the clutch member 22 out of engagement with the clutch member 23 until the clutch on shaft 6 is opened, at which time the cam 30 releases the clutch actuating lever and allows the clutch member 22 to again engage the clutch member 23. The clutch shifting lever for shifting the clutch member 22 is made in two parts indicated at 31 and 32, see particularly Figs. 3 to 6, inclusive. These parts are pivotally mounted upon pivot pin 33 and are arranged to be locked together by means of a latch 34 pivotally mounted upon an arm projecting downwardly from the part 31 and arranged to engage a lateral projection 35 from an arm projecting downwardly from the part 32. A compression spring 36 acting on the outer end of part 31 tends to force the clutch member 22 upwardly into engagement with the clutch member 23, while a compression spring 37 interposed between the lug on part 31 and the latch 34 presses the latch 34 downwardly against the projection 35. The latch 34 is arranged to be engaged by a trip dog 38 pivotally mounted upon the rear end of the starting lever 39. The trip dog 38 when the machine is at rest with the parts in stopped position is held in engagement with the end of latch 34 by means of a compression spring 40 interposed between a lug on the starting lever 39 and the trip dog. Movement of the trip dog under the force of the spring 40 is limited by coöoperating lugs on the starting lever and on the upper end of the trip dog.

30 The construction of clutch shifting lever and tripping devices above described is such that the clutch member 22 may be shifted with certainty to start and stop the machine and to permit the cam carrying gear 9 to be rotated independently of the clutch members 22 and 23, and it is also such that at the completion of a cycle of operations the machine will be stopped whether or not the starting lever 37 is kept depressed by the operator. Fig. 3 shows the position of the parts with the machine in stopped position. To start the machine the forward end of lever 39 is depressed by the operator, thereby disengaging latch 34 from projection 35 and permitting the spring 36 to move the clutch member 22 into engagement with clutch member 23. The gear 9 is then driven from the shaft 16 through worm gear 17 and clutch members 22 and 23, the shaft 6 and therefore gears 18 and 12 being stationary at this time. This movement of clutch member 22 and part 31 of the clutch shifting lever moves the latch 34 out of engagement with trip dog 38 and the parts assume the position indicated in Fig. 4. It will be noted that when latch 34 is raised from projection 35 to disconnect the two members of the clutch shifting lever that clutch member 22 will be moved into engagement with clutch member 23 whether or not cam 29 is in engagement with the clutch shifting lever. The machine can thus be started into operation while the clutch shifting lever is still engaged by stop cam 29. Fig. 4 indicates the position of the parts after clutch member 22 has engaged clutch member 23 and while part 32 of the clutch shifting lever is still held raised by stop cam 29. As soon as stop cam 29 moves from beneath part 32 of the clutch shifting lever this part drops to the position indicated in Fig. 5, thereby causing the latch 34 to again engage projection 35 and lock the two members of the clutch shifting lever together. Fig. 6 indicates the position of the parts while the clutch shifting lever is engaged by cam 30. The cam 30 is slightly lower than cam 29 and does not raise part 32 of the clutch shifting lever high enough to cause the latch 34 to be engaged by trip dog 38. When, therefore, the cam 30 passes from beneath part 32 of the clutch shifting lever the clutch member 22 can again be moved into engagement with clutch member 23. At the end of the cycle of operations cam 29 engages part 32 of the clutch shifting lever and returns the parts to the position indicated in Fig. 3. After the machine is started latch 34 is out of engagement with trip dog 38 and the clutch shifting lever is operated to shift member 22 into and out of engagement with clutch member 23 and finally stop the machine independently of the trip dog and starting lever so that the machine will be stopped at the completion of a cycle of operations regardless of the position of the starting lever and the machine can only be started a second time by releasing the starting lever and depressing it again.

40 In the machine illustrated in the draw-

ings the parts come to rest as the machine is stopped with both the upper and lower needles in retracted position. It is desirable that provision be made for permitting the mechanism for actuating the needles to be moved slightly while the machine is at rest so as to bring one or both needles into a convenient position for threading. To enable the actuating mechanism for the needles to be so moved without any danger of permanently displacing the mechanism with relation to the other actuating mechanisms of the machine the locking plate 21 on the cam carrying gear 9 is cut away as indicated at 41 in Fig. 2. This forms a recess to receive the locking plate 20 when the parts are in stopped position and enables the sewing mechanism to be moved enough to give the desired result. When the machine is started the sewing mechanism is at once returned to its original position in case it has not been returned to this position by the operator before starting the machine.

The nature and object of the present invention having been indicated and a construction embodying the several features of the invention in their preferred form having been specifically described, what is claimed is:

1. Driving and stopping mechanism for button hole sewing and other machines, having in combination, a cam carrying actuating and controlling gear, a second gear, driving mechanism for rotating the controlling gear independently of the second gear, driving mechanism for rotating the second gear and controlling gear simultaneously, means controlled by the controlling gear for throwing said driving mechanisms into and out of operation acting to throw one mechanism out of operation as the other is thrown in, and connections between the controlling gear and the second gear for locking the second gear against displacement while its driving mechanism is thrown out.

2. Driving and stopping mechanism for button hole sewing and other machines, having in combination, actuating and controlling mechanism, a second actuating mechanism, driving mechanism for driving the actuating and controlling mechanism independently of the second actuating mechanism, driving mechanism for driving the second actuating mechanism and the actuating and controlling mechanism simultaneously, means controlled by the controlling mechanism for throwing said driving

mechanisms into and out of operation acting to throw one mechanism out of operation as the other is thrown in, and connections between the controlling mechanism and the second actuating mechanism for locking the second actuating mechanism against displacement while its driving mechanism is thrown out.

3. Driving and stopping mechanism for button hole sewing and other machines, having in combination, an actuating gear provided with a blank space extending over a portion of its periphery, a pinion engaging the gear during a portion of its rotation and registering with the blank space during another portion of the rotation, a locking segment carried by said pinion, a locking plate carried by said gear arranged to engage the locking segment and lock the pinion against rotation while the pinion registers with the blank space, a second pinion meshing with said gear, independent driving means for each pinion, and means for throwing said driving means into and out of operation acting to throw one driving means out of operation as the other driving means is thrown into operation.

4. Driving and stopping mechanism for button hole sewing and other machines, having in combination, an actuating gear, driving mechanism therefor comprising a clutch, a two part clutch shifting lever, a spring acting on one part when disconnected from the second part to throw in the clutch, a cam acting on the second part when the parts are connected to throw out the clutch, a latch arranged to connect the parts when the second part is released by the cam, and a trip for the latch.

5. Driving and stopping mechanism for button hole sewing and other machines, having in combination, an actuating gear, driving mechanism therefor comprising a clutch, a two part clutch shifting lever, a spring acting on one part when disconnected from the second part to throw in the clutch, a cam acting on the second part when the parts are connected to throw out the clutch, a latch trip, and a latch arranged to move out of engagement with the trip when the clutch is thrown in and to connect the parts of the lever when the second part is released by the cam.

EUGENE J. RAY.
